EXHAUST DEVICE FOR INTERNAL COMBUSTION ENGINES

Pierre Ernest Mercier, Paris, France

Application January 30, 1940, Serial No. 316,321
In France February 1, 1939

8 Claims. (Cl. 60—29)

The present invention relates to improvements in exhaust devices for internal combustion engines, more particularly as applied to flying machines.

When the presence of a wind screen or of any hindrance in the vicinity of the exhaust parts makes impossible to use separate exhaust pipes distributed along the whole periphery of a cowling-motor block, which is circular, or the like, the invention provides for the use of individual flared mouth pipes which, instead of ending in the open air, enter tangentially a toroidal space common to several cylinders. The exhaust of gases admitted in the exhaust manifold enclosing the said toroidal space is preferably managed along blade openings also tangentially to the toroidal surface of the exhaust manifold. This arrangement has the advantage of ensuring a good distribution of the speeds of gases in the interior of the manifold by the effect of the helicoidal displacement of such gases, contrary to the normal practice which gives way to irregular whirling phenomena and thus increases the loss of pressure which the gases have to overcome in order to get out and facilitates the occurrence of flames at the level of the exhaust openings.

In order to increase the ease of manufacture and of repair inherent to individual exhaust pipes, the manifold according to the invention is preferably made of similar or identical elements, each of which is formed by the insertion of a cylinder pipe on a toroidal section, all such elements being connected together by means of removable collars, also used for fixing the manifold in the cowling.

The outlet slots towards the open air may with advantage be directed along the extension of a cylinder pipe and be distributed at any places on the manifold, if the same is continuous. If not, there must be at least one outlet slot at each end of a partial manifold.

In the last case, the use of the manifold may be limited to the region where direct exhaust is to be avoided, separate flame-screens being used in the other regions of the motor cowling.

The invention is illustrated by way of example by means of the appended drawing which relates to the particular case of a continuous manifold and to its application to an engine with radially disposed cylinders.

Figure 1 is a partial side view of a device according to the invention, in its cowling.

Figure 2 is a face elevation of the same.

Figure 3 is a partial section along line III—III 55

of Figure 2 and Figure 3A is a similar section on line IIIA—IIIA of Figure 2, while

Figures 4 and 5 show the manner in which two adjacent elements of the manifold are assembled.

There are shown in the figures at 1, the external contour of the cowling, at 2 one of the engine's cylinders, at 3 an individual flared mouth pipe, such as commonly used, inserted tangentially into manifold 4. Number 5 is a two use pipe comprising the combination of the insertion of an individual flared mouth pipe with an outlet slot 10.

By way of additional example, there is a schematically shown at 6 the carburetter which, according to a special disposition, is fed from the bottom by means of an air duct 7 originating at the rear.

It is easily visible in Figure 2 that the manifold is made of neighbouring segments, such as 8 and 9, one method of junction of which is visible in Figures 4 and 5 which disclose small swells 11, 12 on sections 8, 9 caught in a curved section ring made of two parts 13, 17 hinged at 14 and having a lock 15 retained closed by a pin 16.

The invention is, of course, not limited to the modifications described and shown by way of examples, but is susceptible of numerous adaptations which the man of the art may introduce according to the kind of engine to be equipped, the shape of the cowling, etc.

What I claim is:

1. An exhaust device for internal combustion engines, comprising in combination a toroidal manifold which is transversely of substantially round cross section, a plurality of flared mouth pipes opening individually from said cylinders in a common direction substantially parallel to the toroidal axis and connecting upon the exterior of the manifold tangentially into the interior of said manifold, an engine cowling, and a plurality of flared mouth outlet pipes opening tangentially from the interior of said manifold and tangentially to the engine cowling in a common direction substantially parallel to said axis into the open air.

2. An exhaust device for internal combustion engines comprising in combination, a toroidal manifold, which is transversely of substantially round cross section, a plurality of flared mouth pipes opening individually from said cylinders in a common direction substantially parallel to the toroidal axis and connecting upon the exterior of the manifold tangentially by a slot into the interior of said manifold, an engine cowling, and a plurality of flared mouth outlet pipes opening

tangentially from the interior of said manifold and tangentially by a slot to the engine cowling in a common direction substantially parallel to said axis into the open air.

3. An exhaust device for internal combustion engines comprising in combination, an engine cowling, a toroidal manifold constituted of a plurality of slightly arched units along its periphery, each having a substantially round transverse cross section, a plurality of individual flared mouth pipes, each of them opening in a direction substantially parallel to the toroidal axis from one cylinder tangentially exteriorly upon said periphery by a slot into the interior of one section of the said manifold and a plurality of flared mouth outlet pipes each of them opening tangentially from said manifold and tangentially by slots to the engine cowling in a common direction substantially parallel to said axis into the open air.

4. An exhaust device for internal combustion engines comprising in combination, an engine cowling, a toroidal manifold constituted of a plurality of slightly arched units along its periphery, each having a substantially round transverse cross section, a plurality of individual flared mouth pipes, each of them opening in a direction substantially parallel to the toroidal axis from one cylinder tangentially exteriorly upon said periphery by a slot into the interior of one section of the said manifold and a plurality of flared mouth outlet pipes each of them opening tangentially from said manifold and tangentially by slots to the engine cowling in a common direction substantially parallel to said axis into the open air and there being removable collars serving to secure said manifold units one to the other and in the common engine cowling, and swells or flanges upon said units cooperating with said collars.

5. An exhaust device for internal combustion engines comprising, in combination, an engine cowling, a toroidal manifold constituted of a plurality of slightly arched units along its periphery, each having a substantially round transverse cross section, a plurality of individual flared mouth pipes each of them opening in a direction substantially parallel to the toroidal axis from one cylinder tangentially exteriorly upon said periphery by a slot into the interior of one section of the said manifold and a plurality of flared mouth outlet pipes each of them opening tangentially from said manifold and tangentially by slots to the engine cowling in a common direction substantially parallel to said axis into the open air and there being removable collars serving to secure said manifold units one to the other and in the common engine-cowling, and swells or flanges upon said units cooperating with said collars, the said exhaust device comprising also individual flared pipes opening directly from the cylinders into the open air independently of any passage into the manifo. 1.

6. An exhaust device for internal combustion

engines comprising, in combination, an engine cowling, a toroidal manifold constituted of a plurality of slightly arched units along its periphery, each having a substantially round transverse cross section, a plurality of individual flared mouth pipes, each of them opening in a direction substantially parallel to the toroidal axis from one cylinder tangentially exteriorly upon said periphery by a slot into the interior of one section of the said manifold and a plurality of flared mouth outlet pipes each of them opening tangentially from the exterior of said manifold and tangentially by slots to the engine cowling in a common direction substantially parallel to the toroidal axis into the open air and there being removable collars serving to secure said manifold units one to the other and in the common engine-cowling, and swells or flanges upon said units cooperating with said collars, the number of outlet pipes being inferior to the number of cylinder pipes.

7. An exhaust device for internal combustion engines comprising, in combination, an engine cowling, a toroidal manifold constituted of a plurality of slightly arched units along its periphery, each having a substantially round cross section, a plurality of individual flared mouth pipes, each of them opening in a direction substantially parallel to the toroidal axis from one cylinder tangentially exteriorly upon said periphery by a slot into the interior of one section of the said manifold and a plurality of flared mouth outlet pipes each of them opening tangentially from the exterior of said manifold and tangentially by slots to the engine cowling in a common direction substantially parallel to the toroidal axis into the open air and there being removable collars serving to secure said manifold units one to the other, and swells or flanges upon said units cooperating with said collars, and in the common engine-cowling the toroidal manifold extending over at least part of the complete circumference.

8. An exhaust device for internal combustion engines comprising, in combination, an engine cowling, a toroidal manifold constituted of a plurality of slightly arched units along its periphery, each having a substantially round transverse cross section, a plurality of individual flared mouth pipes, each of them opening in a direction substantially parallel to the toroidal axis from one cylinder tangentially exteriorly upon said periphery by a slot into the interior of one section of the said manifold and a plurality of flared mouth outlet pipes each of them opening tangentially from the exterior of said manifold and tangentially by slots to the engine cowling in a common direction substantially parallel to said axis into the open air and there being removable collars serving to secure said manifold units one to the other and in the common engine-cowling, only some of the toroidal manifold sections being provided with the flared pipes.
